AIR RAID ALARM

Walter O. Spoon and Jack Dressel, Jr.,
Goldendale, Wash.

Application April 18, 1951, Serial No. 221,691

2 Claims. (Cl. 340—345)

1

This invention relates generally to audible or sonic alarms and more particularly to means for producing at will either a steady or pulsating noise of the siren type which will be both distinctive and penetrating.

It is a principal object of this invention to provide an air raid alarm giving means having a distinctive signal and of which means any number of duplicates can be made whereby, by the widely distributed use of alarm giving means of this type, the distinctive signal will be generally recognized and instantly understood.

It is a second object of this invention to provide an air raid alarm means capable of making use, for its specific purpose, of the existing radios, public address systems, and similar loud speaker systems widely used and well known today.

It is a third object of this invention to provide a signal generating means capable of generating a distinctively, varying electromotive force which can be impressed on an electromagnetic loud speaker to give either an air raid alarm or an all clear signal.

It is a fourth object to provide an electro magnet having an air gap in its magnetic circuit through which air gap may be rotated at a desired speed of rotation a nonmagnetic disc studded with magnetic inserts spaced in said discs in a predetermined pattern whereby the reluctance of said air gap will be varied in accordance with the pattern of travel of said magnetic inserts through said gap and thereby vary the flux density in the iron circuit of said electromagnet to vary the electromotive force generated in an insulated conducting wire coiled on said iron circuit.

It is a fifth object to provide means for varying to a desired pattern the speed of rotation of said nonmagnetic disc.

It is a sixth object to drive said rotating disc with an electric motor and to control the speed pattern of said disc by a switch in the energizing circuit of said motor.

It is a seventh object of this invention to provide a motor driven cam adapted to open and close the switch in the energizing circuit of the disc rotating electric motor to control the speed pattern of the disc.

It is an eighth object of this invention to provide a double throw switch adapted on one throw to energize with said disc motor and said cam motor to generate an air raid warning signal of a desired pulsating pattern and on the other throw to energize said disc motor only to generate an all clear signal of steady pattern.

2

It is a ninth object of this invention to provide signal lights energized by the respective throws of said switch to indicate to the switch operator that the signal being generated is the signal intended to be generated.

How these and other objects are attained will be apparent from the following description referring to the attached drawings in which:

Fig. 1 is a view in perspective of the enclosing cabinet of the apparatus of this invention.

Fig. 2 is a perspective view with the rear enclosure removed of the interior of the cabinet shown in Fig. 1.

Fig. 3 is a plan view looking upward from the underside of the apparatus of Fig. 2.

Fig. 4 is a schematic representation and wiring diagram of the apparatus of Figs. 1, 2 and 3.

Referring now to the drawings, in Fig. 1 the cabinet front panel 11 on which the principal apparatus of this invention is carried is shown mounted on the five sided rear enclosure 12 which forms the remainder of the cabinet for enclosing and protecting the apparatus.

Carried on insulating front panel 11 through clips 13 is insulating base 14 supporting on its underside by screws 15 and 16 disc operating electric motor 17 and cam operating electric motor 18 respectively. Secured by screws 19 to a hub, not shown, fixed to vertical shaft 20, indicated in Fig. 4, of motor 17 is nonmagnetic disc 21 through which have been inserted in a predetermined pattern magnetizable inserts 22. Also carried on base 14 through bracket 23, post 24 and spacer 25 is shielding conducting case 26 the open bottom of which faces the top of disc 21. Fixed in case 26 in a V shaped permanent magnet (not shown), open downwardly so that its two poles are closely spaced, respectively, over the two rows of inserts 22 of different radius from shaft 20. Wound on the permanent magnet in case 26 is a pick-up coil (not shown) having terminals 27, 28 outside case 26.

Pressed on shaft 29 of cam motor 18 is cam 30. Adapted to ride over the undulating cam surface of cam 30 is roller 31 whose axle 32 is journalled as shown in the free end of resilient lever 33 having its other end secured to the insulating enclosing case 34 of a normally open electric switch having an operating stem 35 guided in case 34 and terminals 36 and 37 extending through case 34. Case 34 is secured to base 14 by screws 38 and so positioned that the switch in case 34 is open as roller 31 rides in a valley of cam 30 and closed as roller 31 rides over a peak of cam 30.

Secured to the back of panel 11 by screws 39 is frame 40 of a double throw manually operated switch having an operating lever 41 journaled on pin 42 in frame 40. As shown in Fig. 1, lever 41 extends through hole 43 in panel 11 for operation from the front side of panel 11. As indicated schematically in Fig. 4, lever 41 is adapted on throw to one side to close switch blades 44 and 45 on blades 46 and 47, respectively, and on throw to the other side to close switch blades 48 and 49 on blades 50 and 51, respectively.

Receptacle 52 having insulated center terminal 53 and side terminal 54 carries lamp 55 and is mounted as shown on the rear of panel 11 with lamp 55 adjacent a hole in panel 11 in which is mounted green lens 56. Receptacle 57 having insulated center terminal 58 and side terminal 59 carries lamp 60 and is mounted as shown on the rear of panel 11 with lamp 60 adjacent a hole in panel 11 in which is mounted red lens 61.

Signal output cable receptacle 62 is secured to panel 11 by nut 63 threaded on a reduced section of receptacle 62 extending through a hole in panel 11.

Resistors 64, 65 and 66 are secured to the underside of base 14. The front of the panel 11 is suitably marked to show the proper direction of throw of switch lever 41.

Electric power is supplied to this apparatus through a common type of plug cord 67 connected to terminals L1, L2, as shown.

Wire 68 connects L1 with side terminals 54 and 59 of lamp receptacles 52 and 57. Wire 69 connects L1 with switch blade 59, cam switch terminal 36, and one terminal of condenser 70. Wire 71 connects L2 with one terminal of disc motor 17, one terminal of cam motor, and one terminal of resistor 66. Resistors 64, 65, and 66 are connected in series as shown. Wire 72 connects the other cam switch terminal 37, with the other terminal of condenser 69 and switch blade 46. Wire 73 connects switch blade 48 with the other terminal of disc motor 17 and with switch blade 44. Wire 74 connects switch blades 45 and 49 with the other terminal of resistor 64 and the other terminal of cam motor 18. Wire 75 connects switch blade 47 with lamp terminal 58. Wire 76 connects switch blade 51 with lamp terminal 53. Single conductor shielded cable 77 connects insulated terminal 27 of the pick up coil in case 26 with the insulated center terminal 78 of output receptacle 62. The other terminal of the pick up coil is grounded to case 26. The output cable 77 has its shield grounded at one end to case 26 and at the other end to the metal case of receptacle 62.

Shown diagrammatically only in Fig. 4 is a loud speaker horn 79, its input coil 80 and a cord 81 used to connect the output receptacle center terminal 78 with the loud speaker system of whatever type is required for the particular warning system used.

With a properly energized loud speaker system plugged into the output receptacle of the apparatus described and the apparatus connected to a source of electric power with cord 67 and with the double throw switch lever 41 in the center or neutral position, it is seen from the drawings that no operating part of the apparatus will be energized. However, if it is desired to broadcast a raid alarm, lever 41 can be thrown in the direction of the arrow pointing to the word "Raid" on panel 11. When lever 41 is thus thrown, switch blade 45 is forced to contact blade 41 and switch blade 44 is forced to contact blade

46. When switch blade 45 contacts blade 41, a circuit between terminals L1 and L2 is set up from L1 through wire 68, lamp 60 (behind red lens 61), wire 75, switch blades 41, 45, wire 74, cam motor 18 and wire 71 to L2. The only purpose of the circuit from wire 74, through resistors 64, 65 and 66 to wire 71, paralleling cam motor 18 with the three resistors in series to divide the line voltage L1 to L2 between the lamp 60 and the cam motor 18 according to the voltage requirements of each of them. It is seen that when switch blade 45 and 47 contact lamp 60 will light up behind red lens 61 and the motor 18 will start up causing cam 30 to revolve at constant speed.

At the same time, switch blade 44 will be forced into contact with blade 46 and a second circuit is set up from L1 through wire 69, cam switch terminals 36, 37, wire 72, switch blades 46, 44, wire 73, disc motor 17 and wire 71 to L2. Condenser 70 is connected across cam switch terminals 36, 37 to prevent undue deterioration of the cam switch contacts. It is seen that when switch blades 48, 44 are in contact disc motor 17 will be energized when the cam switch is closed and deenergized when the cam switch is open and since cam motor 18 is revolving at constant speed, roller 31 riding the undulating face of cam 30 will cause lever 33 and stem 35 to periodically energize and de-energize disc motor 17 causing disc 21 to accelerate and decelerate periodically causing a periodical increase and decrease in the rate at which the magnetic inserts 22 change the flux through the iron circuit of the magnet in case 26 and, therefore, cause an electromotive force to be generated in the pick-up coil wound on the magnet in case 26 which will be periodically varying in both frequency and amplitude, thus causing the loud speaker system to emit a penetrating and distinctive sonic alarm signal.

When it is desired to stop broadcasting the alarm lever 41 is returned to its neutral position and the equipment is de-energized. Then, if it is desired to broadcast an all clear signal, lever 41 is thrown in the direction of the arrow on panel 11 pointing to the word "Clear" on the panel. This throw of lever 41 causes switch blades 48 and 49 to contact with blades 50 and 51, respectively. The closing of contact 49 on contact 51 sets up a circuit from L1 through wire 68, lamp 55 (behind green lens 56), switch blades 51, 49, wire 74, cam motor 18, and wire 71 to L2, thus showing a green light on the front of the panel and setting cam motor 18 into operation. At the same throw of lever 41 blade 48 will be put into contact with blade 50 and a circuit will be set up from L1 through wire 69, blades 50, 48, wire 73, disc motor 17 and wire 71 to L2, thus setting the disc motor into operation at constant speed. While cam motor 18 is operating in this case, it does not affect the operation of the disc motor since switch blades 50, 48 energize disc motor directly from L1 and L2. The "Clear" signal will, therefore, not be generally undulating in frequency and amplitude as the "Raid" signal was seen to be, but will be generally constant in the pattern of insertion of inserts 22 into disc 21.

Having thus described a preferred form of the device of this invention and explained its use, we claim:

1. An air raid signal producing mechanism adapted to be controlled by a double throw switch to give an audible steady alarm responsive to one throw of said double throw switch and an inter-

rupted audible alarm responsive to the other throw of said double throw switch, said mechanism comprising in combination a source of electric power, a disk of non-magnetic material, a first electric motor adapted to rotate said disk, a plurality of magnetic inserts in said disk, means forming a magnetic circuit, said magnetic circuit being adapted to include said insert once at each revolution of said disk, an electromagnetic loud speaker, electric circuit means adapted to couple said magnetic circuit with said loud speaker, means for energizing said magnetic circuit and said loud speaker, an electric switch, a rotatable cam, a second electric motor adapted to rotate said cam, said cam being adapted to close and open said switch as said cam is rotated, a double throw switch, and circuit means adapting said double throw switch in one of its throw positions to energize said first motor from said source of power, and in the other of its throw positions to energize said first motor from said source of power through said electric switch and to energize said second motor from said power source.

2. In combination a source of electric power, a disk of non-magnetic material, a first electric motor adapted to rotate said non-magnetic disk, a plurality of magnetic inserts in said disk, said inserts being set into said disk in a desired pattern, means forming a magnetic circuit, said

5
10
15 magnetic circuit means being adapted to overlay said disk whereby the reluctance of said magnetic circuit will vary as said disk is rotated and said magnetic inserts enter and leave said magnetic circuit in a desired pattern, an electromagnetic loud speaker, circuit means adapted to couple said loud speaker to said magnetic circuit, an electric switch, a rotatable cam, a second electric motor adapted to rotate said cam, said cam being adapted to close and open said switch as said cam is rotated by said second motor, a double throw switch, and circuit means adapting said switch in one of its throw positions to energize said first motor from said source of power and in the other of its throw positions to energize said first motor through said electric switch from said source of power and to energize said second motor from said source of power.
